MAGNETICALLY CONTROLLED ADVERTISING, EDUCATIONAL, OR AMUSEMENT DEVICE

Gerald Evan Spicer, St. Albans, England

Application January 8, 1936, Serial No. 58,171
In Great Britain January 10, 1935

6 Claims. (Cl. 35—41)

This invention relates to devices which may be used for advertising, amusement or educational purposes, and which have one or a number of bodies movable over a surface or floating upon or immersed in a liquid, the bodies having a part susceptible to magnetic influence and being adapted to be manoeuvred by means of a magnet, preferably arranged out of sight below the objects.

According to the present invention, in a device of the kind referred to, the manoeuvrable object incorporates a permanent magnet. The disposition of the magnet is preferably such that the pole at the forward end of the manoeuvrable body is of polarity opposite to that of the manoeuvring magnet by which the object is directed, and it will be appreciated that attraction will take place between the pole of the manoeuvring magnet and that at the forward end of the manoeuvrable object. The invention has a particular application to advertising devices and toys in which a manoeuvrable object comprises a body floating upon or immersed in liquid, and it is therefore with reference to this particular application that the following description deals. If the manoeuvring magnet be disposed as in the preferred form of the invention below the tank or the like containing the liquid, the forward end of the floating object will tend to take up a position so as to be vertically disposed over the manoeuvring magnet, whereafter movement of the latter will cause the floating object to be forwardly and realistically directed. Conveniently, the magnet incorporated in the floating object serves also as a keel. Provision is made in the proposed form of the invention for positively supporting and directing the manoeuvring magnet, and further by use of an electro-magnet for manoeuvring, the strength may be conveniently increased for the purpose of submerging a normally floating object.

In order that the invention may be more readily understood, one form will be described with reference to the accompanying drawings, in which:

Figure 1 is a plan view of a device according to the invention;

Figure 2 is a sectional elevation of the device taken along the line II—II of Figure 1;

Figure 3 is a view of a model boat for use with the device shown in the previous figures; and

Figure 4 shows in diagrammatic form a proposed electrical circuit for operating an electro-manoeuvring magnet.

In the form of the invention illustrated, the

device comprises a shallow open-topped tank 1 containing water 2. In order to produce a realistic effect, the tank also contains representations of land, as at 3, in the form of coast-lines. Model boats, such as that illustrated in Figure 3, are adapted to float on the surface of the water. It is also proposed to provide a submarine, such as that shown at 5, which normally floats on the surface but which is adapted to be sunk in a manner as hereafter described.

Each floating object incorporates a permanent magnet 6, as shown in Figure 3, extending substantially parallel with the longitudinal centre-line of the object and may conveniently form the keel of the boat to preserve its balance. For the purposes of this description, it is presumed that the north-seeking pole is situated towards the prow of the model. Below the surface of the tank 1 is disposed an electro-magnet comprising a core 7 of soft iron or the like and a surrounding coil 8 through which a current is passed.

The magnet is carried in a carriage 9 so that the uppermost pole thereof is of opposite polarity to that at the prow of the boat to be manoeuvred, i. e. the south-seeking pole. Inasmuch as unlike magnetic poles attract, it will be understood that the boat is attracted by the north-seeking pole of the electro-magnet when current is passed, and by suitably moving the magnet the boat may be manoeuvred.

In the preferred form of the invention illustrated, the carriage 9 is supported on rods 10 and 11 disposed at right-angles to each other, each being parallel to the appropriate pair of sides of the tank and passing through holes suitably provided for the purpose in the carriage 9. The rods 10 and 11 are attached at their extremities to

pairs of endless chains 12 and 13 which are of any desired construction. The pair of chains 12 pass round pairs of sprockets 14 and 15 at the

sides of the tank, and sprockets 14 are mounted on a common shaft 16 operated by means of a handle 17. It will be appreciated that rotation of the handle 17 will move the carriage 9 laterally along the rod 10. In a similar manner the

chains 13 pass round pairs of sprockets 18 and are mounted on the common shaft 20 rotatable by means of the handle 21. Rotation of the handle 21 thus moves the carriage along the rod 11.

Simultaneous rotation of the handles 17 and 21 produces angular or diagonal movements of the carriage. In order to indicate the position of the carriage 9, the rods 10 and 11 are provided at one extremity with pointers 22 and 23

extending from the interior of the device through slits in the sides of the casing.

In Figure 4 a diagrammatic electrical circuit is shown for operating the electro-magnet. Three cells 24 are connected in series and to one plate of one cell an end of the coil 8 is connected. The other end of the coil is connected to a switch 25 whereby one, two or three cells may be put in circuit, thereby increasing the strength of the magnet. Normally floating objects such as the submarine 5 can thus be submerged, and thereafter manoeuvred below the surface of the liquid contained in the tank.

Although the invention has been described as incorporating an electro-magnet, it could of course be used with a permanent magnet, but it will be appreciated that use of an electro-magnet offers the advantage that one boat may be left to manoeuvre another by switching off the current, while there is also the additional advantage of being able to submerge normally floating objects by increasing the current.

It will also be appreciated that the construction of the device may be varied within wide limits; for example the representation of land may be cut out of wood or other suitable material and placed in the tank, or it may be formed as a pressing integrally with the bottom of the tank.

It is contemplated that a device such as that above described is particularly applicable for advertising, amusement and educational purposes.

It is further contemplated that floating bodies other than boats may be used; thus, the device may be used to represent an aquarium with creatures therein.

Where the device is intended for use in manoeuvring objects supported upon a surface, such for example as motor cars and other toys running upon roads, etcetera, it is of course not necessary to have the liquid.

What I claim is:—

1. A magnetic-controlled amusement device comprising a substantially plane supporting element, a body supported thereby, a permanent bar magnet carried by the body parallel to the general plane of the supporting element, a movable manoeuvring magnet, and means for shifting the manoeuvring magnet in any desired direction in a plane parallel to the general plane of the supporting surface and moving said body and permanent magnet under the influence of said manoeuvring magnet, the pole at the forward end of said permanent magnet being of opposite polarity to the effective polarity of the manoeuvring magnet.

2. A device of the class described including a tank having liquid therein, a body adapted to be positioned in the tank immersed in the liquid, a permanent bar magnet carried parallel to the surface of the liquid, a manoeuvring magnet having an effective pole of opposite polarity to the pole at the forward end of the permanent magnet, and means carried by the tank and connected with the manoeuvring magnet effecting movement in a horizontal plane in any desired direction of said manoeuvring magnet whereby the body and permanent magnet will be moved under the influence of said manoeuvring magnet.

3. A device of the class described including a liquid containing tank, a body immersed in liquid carried in the tank, a permanent bar magnet carried by the body substantially parallel to the surface of the liquid, a manoeuvring magnet, and means carried by the tank effecting movement of the manoeuvring magnet in any desired direction in a horizontal plane, said manoeuvring magnet being of bar form and of such a length and arrangement that the effect of one of its poles is negligible compared to that of the effective second pole on said permanent magnet in the body whereby attraction between the effective pole and the manoeuvring magnet and the pole at the forward end of the body with consequent movement of the body under the influence of said manoeuvring magnet takes place.

4. A device of the class described including a tank having liquid therein, a body adapted to float upon the liquid contained in the tank, a permanent magnet carried by the body substantially parallel to the surface of the liquid, a manoeuvring magnet, a carriage supporting the manoeuvring magnet and having rods disposed at right angles to each other, said rods being adapted to be moved for shifting the manoeuvring magnet in any desired direction in a horizontal plane, said permanent magnet having a pole at its forward end of opposite polarity to the effective pole of said manoeuvring magnet and said body being adapted to be moved under the influence of said manoeuvring magnet.

5. A device of the class described including a tank having liquid therein, a body in the tank immersed in the liquid and having a permanent bar magnet disposed substantially parallel to the surface of the liquid, a manoeuvring magnet, a carriage supporting the manoeuvring magnet and having rods disposed at right angles to each other, and an endless chain connected with each of the rods at their opposite corresponding ends, said endless chain passing over sprocket wheels, certain chains being adapted to be rotated to cause the rod to be traversed, said permanent magnet having a pole of opposite polarity to the effective pole of the manoeuvring magnet whereby shifting of the manoeuvring magnet will cause shifting of the body and permanent magnet under the influence of said manoeuvring magnet.

6. A device of the class described including a tank, a body therein adapted to float on or be immersed in liquid carried in the tank, a permanent bar magnet carried by the body, said magnet being disposed substantially parallel to the surface of the liquid, a manoeuvring magnet having an effective pole of opposite polarity to the pole at the forward end of the body, mechanical means for supporting a manoeuvring electromagnet and permitting shifting thereof in any desired direction in a horizontal plane whereby shifting of said manoeuvring magnet will cause shifting of the body under the influence of said manoeuvring magnet, and means for increasing the effectiveness of the manoeuvring electromagnet for causing the body to increase or lessen its depth within the liquid in the tank.

GERALD EVAN SPICER.
